UNITED STATES PATENT OFFICE.

WILLIAM HENRY WILLIAMS, OF BIRMINGHAM, ENGLAND.

MEANS FOR CASTING METAL.

1,302,114.

Specification of Letters Patent. Patented Apr. 29, 1919.

Application filed March 19, 1918. Serial No. 223,445.

To all whom it may concern:

Be it known that I, WILLIAM HENRY WILLIAMS, subject of the King of Great Britain, and residing at Bromford Lane, Erdington, 5 Birmingham, England, have invented certain new and useful Improvements in Means for Casting Metal, of which the following is a specification.

This invention comprises improvements in 10 and relating to the methods and means of casting metals, in which the metal is melted in a crucible or pot placed in a furnace and subsequently conveyed out of the furnace for pouring the metal into ingot or strip molds 15 or into any other molds used in casting operations. The invention is distinct from tilting furnaces in which metal is melted and poured out bodily tilting the furnace.

In accordance with my invention I provide 20 a receptacle or cradle to receive a pot or crucible for molten metal the receptacle or frame comprising a tilting device whereby the pot or crucible may be bodily tilted pivoting about a point which is about the position 25 of the spout or nose of the pot. The receptacle is preferably on wheels or runners and may travel on a track to the molds and in the case of strip, or ingot, or tube molds the latter may conveniently be arranged in 30 a rack alongside which the receptacle carrying the pot may travel.

In the rack or stand the molds can be placed so as to be all at the same angle and in correct position for receiving the poured 35 metal as the pot is tilted by its cradle into pouring position. The cradle may be tilted by a lever or other mechanical power multiplying device so that the tilting of the pot presents little or no difficulty and as by the 40 position of the rack and the carriage track the relation between the pot and the mold is correctly established, no spilling of metal is likely to occur and the pouring operation is rendered easy and safe.

45 On the drawings:

Figure 1 is an elevation of a rack or stand with ingot or like molds supported therein, and the pot or crucible receptacle or cradle adjacent thereto.

50 Fig. 2 is a side elevation of Fig. 1 looking from the left.

Fig. 3 is a plan of the receptacle or cradle of the crucible or pot.

55 Fig. 4 is a side elevation of the cradle and the upper end of a mold showing the cradle and pot in tilted position.

Fig. 5 is a perspective view of the cradle and fork of the tilting lever in the position seen at Fig. 1.

In this example of my invention I have 60 shown the cradle mounted on a traveling carriage or running frame on a track *a* alongside a rack or frame *b* which has a series of notches or divisions at intervals along it to accommodate molds *c*. The rack 65 or frame *b* is arranged so that the molds *c* placed therein will be at a suitable angle for filling and all will be at the same angle. Between each pair of notches or divisions in the frame *b* I may arrange two screw studs 70 *d* one near the upper part of the frame and one near the lower part, and on each of these studs *d* a yoke bar *e* may be arranged adapted to pass across say two molds and behind each yoke bar is a handle nut *f* for applying pressure. By this means the two halves of each mold may be more rapidly clamped together than by the rings and wedges now commonly used, as two molds may be dealt with simultaneously, and further the molds 80 may thereby be secured in the rack *b*. The molds preferably have a receiving lip or mouth *g* on one side directed toward the rack and communicating with the interior of the mold.

85 The traveling carriage may comprise any suitable frame provided with runners for traveling on the track *a* aforesaid and has two upstanding sides or brackets *h* providing bearings, or a fulcrum, for a forked 90 lever *j*. Beyond the bearings the lever *j* continues down and the extremities of its fork *k* receive and engage the squared or other appropriate projections *l* of a cradle *m* in which the pot *n* of metal is received. The 95 cradle *m* may comprise for example one or more rings *o* for encircling the pot and a central cranked bottom bar *p* on which the pot may rest.

The axle *q* on which the forked lever is 100 mounted in the sides or brackets *h* may be curved at the part *r* between the bearings to pass around the front of the pot *n* just below the spout to form a rest or support when the pot is tilted.

105 As the lever *j* is swung down its fork extremities *k* are raised and raise the cradle *m* in which the pot *n* is placed, thus tilting the pot into pouring position, see Fig. 4.

I claim:

110 1. For casting metals and alloys the combination of a cradle for a crucible of molten

- metal or alloy, means for raising and tilting said cradle, said means comprising a forked lever with the fork ends connected to the cradle, and a stand portion providing a fulcrum for said lever adjacent to the portion occupied by the spout of the crucible when in said cradle.
2. For casting metals and alloys the combination of a cradle for a crucible of molten metal or alloy, means for raising and tilting said cradle, said means comprising a forked lever with the fork ends connected to the cradle, and a stand portion providing a fulcrum for said lever adjacent to the position occupied by the spout of the crucible when in said cradle, said stand comprising a base part with upstanding brackets which provide the fulcrum for the lever.
3. For casting metals and alloys, the combination of a cradle for a crucible of molten metal or alloy, means for raising and tilting said cradle, said means comprising a forked lever with the fork ends connected to the cradle, and a stand portion providing a fulcrum for said lever adjacent to the position occupied by the spout of the crucible when in said cradle, said stand portion being provided with a carriage or running frame.
4. For casting metals and alloys the combination of a cradle for a crucible of molten metal or alloy, means for raising and tilting said cradle, said means comprising a forked lever with the fork ends connected to the cradle, and a stand portion providing a fulcrum for said lever adjacent to the position occupied by the spout of the crucible when in said cradle, said stand comprising a base part with upstanding brackets which provide the fulcrum for the lever, and said base part being provided with a carriage or running frame.
5. For casting metals and alloys, the combination of a cradle to receive a crucible of molten metal or alloy, means for raising and tilting said cradle and said crucible, said means comprising a forked lever with the fork ends connected to the cradle, and a stand portion providing a fulcrum for said lever adjacent to the position occupied by the spout of the crucible when in said cradle, a rack for supporting molds with a track adjacent thereto, and a carriage on said track on which carriage said stand portion is mounted so that said crucible in said cradle may be tilted by said lever to pour metal into any mold in said rack.
6. For casting metals and alloys, the combination of a cradle for a crucible of molten metal or alloy, means for raising and tilting said cradle, said means comprising a forked lever with the fork ends connected to the cradle, and a stand portion providing a fulcrum for said lever adjacent to the position occupied by the spout of the crucible when in said cradle, said stand comprising a base portion with upstanding brackets which provide the fulcrum for the lever, and said base portion being provided with a carriage or running frame, a rack for supporting molds with a track adjacent thereto on which said carriage may travel, said rack having means for clamping said molds in inclined position therein so that said crucible in said cradle may be tilted to pour metal into any mold in said rack.

In testimony whereof I affix my signature.

WILLIAM HENRY WILLIAMS.
